FRICITION CONTROL FOR CASING SPINNING APPARATUS

Filed Feb. 1, 1929

UNITED STATES PATENT OFFICE

WALTER W. FOSTER, OF WICHITA FALLS, TEXAS

FRICTION CONTROL FOR CASING SPINNING APPARATUS

Application filed February 1, 1929. Serial No. 336,811.

This invention relates to well drilling equipment and it has particular reference to what is generally known to the art as pipe spinning apparatus, that is to say, apparatus 5 designed for the purpose of minimizing the manual effort and danger incident to running and pulling casing or tubing sections, and the invention has for its principal object, with the foregoing in view, to provide 10 apparatus of extremely simple and durable nature, operating off the draw works' line shaft by frictional engagement of two elements in control of a line, which latter is utilized to impart a series of rapid rotary 15 movements to the pipe or casing with little manual effort either by imparting the primary rotation in setting up casing by entwining the line about the pipe in the conventional manner or by tightening the joints by connecting the line to the tongs and applying a 20 series of short hitches thereto.

The invention further aims among its objects to provide casing spinning apparatus in which the power mechanism is capable of 25 ready control of the operator at all times, and by reason of which, there is little or no danger of mishap, such as entangling the operators in the line, shearing the threads of the pipes and joints, which are very prominent 30 disadvantages in the present equipment designed and used for setting up and breaking out casing and tubing.

Yet another and important object of the invention resides in the ease and readiness in 35 which the equipment embodying the invention may be applied for actual operation, such being possible without boring unnecessary holes in the jack post, upon which the invention is designed to operate.

With the foregoing objects as paramount, the invention has further reference to its 40 salient features of construction and arrangement of parts to become manifest as the description proceeds, taken in connection with 45 the accompanying drawings, wherein;

Figure 1 represents a fragmentary view of the jack post of a draw works, showing the invention operatively assembled thereon.

Figure 2 is a side view of the jack post, 50 showing an end view of the draw works'

line shaft, cat head and friction elements operatively assembled.

Figure 3 is a sectional view on line 3—3 of Figure 2.

Figure 4 is a sectional view of the supporting bracket on line 4—4 of Figure 1.

Figure 5 is a lateral cross-sectional view of the supporting bracket on lines 5—5 of Figure 1.

Figure 6 is a fragmentary view of the supporting bracket plate, showing in detail the positioning bushings for the bracket.

Figure 7 is a horizontal cross-sectional view of Figure 6, and

Figure 8 is a sectional view on line 8—8 of Figure 3.

Continuing now more in detail with the invention, it may be here stated that heretofore, in setting up or pulling the casing and tubing assemblies the joints were assembled by placing a few turns of manila rope about the conventional cat head operating on the line shaft, the other end of the rope being similarly entwined about the joint of pipe in the well.

As the elevator lowers a new section down upon the joint, the several turns of rope are slipped upon the end of the section and operators at either end of the rope pull in opposite directions to tighten the latter both around the make-up cat head and the casing. Obviously the casing section is spun into position in the joint, whereupon another section is lifted into position for another operation after having applied the tongs in the usual manner.

This method of spinning in sections is a well known and established practice, but the disadvantages are many, among which are the inability of controlling the speed and friction other than by loosening the ends of the rope to relieve the friction, and in event the rope is wet, it does not readily release and as a consequence, the threads of the section or joint are injured requiring that another section be substituted. Another disadvantage in this old practice resides in the element of danger always present in getting an operator entangled in the rope and inquiring him, sometimes fatally.

The present invention therefore affords a means by which the line is always under the operator's control, and is so devised that in any emergency, such as improper seating of the section in the joint, entanglement of an operator, if possible in the present arrangement, or any like incident the operator may instantly release friction on the rope and relieve the applied power.

Accordingly, reference is made to Figures 1 and 2, showing fragmentarily the conventional jack post 1 and draw works' line shaft 2 with the make-up cat head 3 fixed upon the end thereof by means of key 4. It will be noted that the fact that the invention operates off the line shaft 2 does not in any way affect the proper function of the cat head, or any other element for that matter, in view of the fact that a special cast cat head is provided having an inner flange 5, which has a peripheral V shaped channel in cross-section corresponding with which is a friction wheel 6 therebelow, having as an integral part thereof a drum 7.

Affixed to and wound about the drum 7 is a line 8, which latter will be again and more specifically referred to later.

The object of the assembly is to bring the friction wheel 6 into engagement with the V channel of the cat head flange 5 in the manner shown in dotted lines in Figure 2 and the motion of the cat head will be thereby imparted to the friction wheel 6, to cause the line 8 to be wound about the drum 7.

Friction between the wheel 6 and flange 5 is obtained by means of suitable asbestos brake band material 9 disposed in the V channel of the flange. It is intended that this material be in two circular pieces and riveted or otherwise suitably secured on each angle of the channel, but there is no definite arrangement shown since this feature involves no especial novelty in the invention.

With reference now to Figure 3; the friction wheel 6 is shown as being mounted upon a solid core 10, with rollers 11 interposed between the outer periphery of this core and the inner periphery of the drum. This arrangement allows the drum 7, which is an integral part of the friction wheel 6, to freely rotate about the core 10, which latter is held against rotation as will become apparent presently. The core 10, as may be observed in Figure 3, has a flange 12, which retains the rollers 11 in place. At points parallel to the center of the core 10, as observed in Figure 8 are holes 13 and 14, the purpose of which will be presently made clear.

A plate 15 as an integral part of an operating lever 16 is affixed by bolt 17 extending through the plate 15 and into hole 14 in the core 10, and it is important to note that the pivotal point of the friction wheel 6, is eccentrically situated in order that the rotating axis of the wheel may be displaced to

bring the outer periphery thereof into engagement with the V channel without affecting rotation of the wheel.

The oscillating pivot of the wheel 6 is formed by a short stationary shaft 18, integral with a bar 19, entering hole 13 of core 10 and capable of sliding movement in the bracket 20 by which the apparatus is applied to the jack post 1, as apparent in Figures 1 and 2. Collars 21 are situated on the shaft 18, opposing the wheel 6 to maintain its position relative to the V channel of the flange 5, and are held secure by said screws 22. By releasing these collars the friction wheel may be moved laterally to align its periphery with the V channel of the flange with little difficulty.

Referring now to the bracket and adjustable bar 19, it may be mentioned that the plate 20 is designed to be applied to the jack post immediately opposite the drilling drum shaft journal box (not shown) in order that additional holes will not be necessary to support the same. It is simply necessary to remove the nuts from the bolts supporting the said journal box, apply the plate in the manner shown in Figure 1 and replace the nuts.

It is sometimes the case however, that the holes in the plate 20 do not properly align with the bolts supporting the drum shaft journal box, and to avoid difficulty of this nature, a device such as shown in Figures 6 and 7 has been provided, which consists of a bushing 23, of a thickness equal to that of the plate 20, and having an opening 24 therein eccentrically disposed. In applying the plate 20, the bushings 23 are turned to bring the opening to aligned position with the bolts supporting the journal box on the jack post at the right of the post 1 shown in Figure 2. While Figure 6 is only a fragmentary view of the plate 20, there are several holes in the plate to receive bolts passing through the post 1; hence it is necessary to provide a bushing as designated by character 23 in Figure 6, for each of these holes. When one of the bolts is passed through the opening 24 in the bushing, the bushing may be turned in order that the other bolts may be inserted by alining the said opening 24 in each of the other bushings to receive the bolts. This feature is provided in order that uniformity of size and structure may be carried out in the construction of the plate 20.

The plate 20 has integral ribs 25, between which is received the bar 19, which, as apparent in Figure 5 is dove-tailed in order that its movement will be limited to the longitudinal. A short lateral bar 26, likewise dove-tailed is disposed across the channel in which the bar 19 is disposed, and through each of these short bars is threaded a screw 27, the ends of which abut the ends of the bar 19. By manipulating these screws, the bar 19 is moved longitudinally to raise or lower the

oscillating pivot of the frictional wheel 6, and thus cause the wheel 6 to be moved relative to the flange 5 of the cat head.

A spring 28 being attached to post 1 and the lever 16 to bring the latter upward to assure the disengagement of the friction wheel 6 and the flange 5 when inoperative.

In a companion application for Letters Patent filed February 1, 1929, Serial Number 336,812, is shown the line assembly and the means co-operating with the present invention for cushioning or allowing the line to yield to the strain thereupon in event the section is improperly seated in the joint. 10 15 This assembly consists of a weight suspended upon the end of the line 8, after the latter has been threaded over a yieldingly suspended sheave near the top of the derrick, not shown. To the weight is connected a short 20 25 line, which latter is wound about the casing section being set up, and as the lever 16 is depressed to bring the friction wheel into engagement with the constantly moving flange 5, the line 8 is wound upon the drum 7, causing the said weight to ascend, the yielding support of the sheave equalizing the strain upon the joint as the weight rises.

While the elements above referred to are important in the proper operation of the invention herein shown, they have not been dealt with in great detail since they form the subject of other claims.

Manifestly the construction shown is capable of considerable modification and such modification as is considered within the scope and meaning of the appended claims is also considered within the spirit of the invention.

What is claimed is:

1. In an apparatus for setting up and breaking out casing, the combination including a pair of rotary, inter-engaging elements arranged for relative movement and a mounting for one of said elements comprising a stationary channeled member and a bar disposed for sliding movement in the channel of said member and having an integral part for supporting one of said elements, and means bearing against either end of said bar and stationary relative to said channeled member whereby to effect adjustments of said bar and the element mounted thereon.

2. In an apparatus for setting up and breaking out casing, the combination including rotary inter-engaging elements, one of which is capable of movement relative to the other, a mounting for said movable element, said mounting comprising a channeled member in a fixed plane at right angles relative to the rotating axis of said movable element, a bar slidably mounted in the channel of said member and having a protuberance receiving said movable member, means for holding said bar normally stationary and means stationary relative to said channeled member for receiving said latter means

whereby the same may be adjusted to effect movement of said bar to thereby adjust the position of said movable element relative to its companion element.

In testimony whereof I affix my signature. 70
WALTER W. FOSTER.
